US00D689868S

(12) **United States Design Patent**
Ishikawa et al.

(10) **Patent No.:** US D689,868 S
(45) **Date of Patent:** ** Sep. 17, 2013

(54) **SCANNER**

(71) **Applicant:** **Canon Denshi Kabushiki Kaisha**,
Chichibu (JP)

(72) **Inventors:** **Tetsurou Ishikawa**, Tokyo (JP); **Tatsuya Nishi**, Narashino (JP); **Teruhiko Kitamura**, Tokyo (JP)

(73) **Assignee:** **Canon Denshi Kabushiki Kaisha**,
Saitama-ken (JP)

(**) **Term:** **14 Years**

(21) **Appl. No.:** 29/449,115

(22) **Filed:** **Mar. 14, 2013**

Related U.S. Application Data

(62) Division of application No. 29/416,372, filed on Mar. 21, 2012, now Pat. No. Des. 682,834.

(30) **Foreign Application Priority Data**

Sep. 21, 2011 (JP) 2011-021551

CLAIM

The ornamental design for a scanner, as shown and described.

DESCRIPTION

FIG. 1 is a perspective view of a scanner in which the feeding tray is in the open position;

FIG. 2 is a front view in which the feeding tray is in the open position;

FIG. 3 is a rear view in which the feeding tray is in the open position;

FIG. 4 is a left side view in which the feeding tray is in the open position;

FIG. 5 is a right side view in which the feeding tray is in the open position;

FIG. 6 is a plan view in which the feeding tray is in the open position;

FIG. 7 is a bottom view in which the feeding tray is in the open position; and,

FIG. 8 is a perspective view in which the feeding tray and the support plates are in the open position.

1 Claim, 8 Drawing Sheets
